UNITED STATES PATENT OFFICE.

WALTER E. PREBLE, OF NEW YORK, N. Y.

DESIGN FOR A LINK FOR DRYING-CHAINS OF ENVELOPE-MACHINES.

SPECIFICATION forming part of Design No. 16,999, dated November 23, 1886.

Application filed October 9, 1886. Serial No. 215,811. Term of patent 14 years.

To all whom it may concern:

Be it known that I, WALTER E. PREBLE, of the city, county, and State of New York, have invented and produced a new and original Design for Links of Drying-Chains of Envelope-Machines, of which the following is a specification, reference being had to the accompanying drawing, forming a part thereof.

The drawing represents a view in perspective of a link of drying mechanism in envelope-machines embodying my new and original design.

This design embraces new and distinct configurations of the side portions of the link, as hereinafter described, and pointed out in the claims.

A distinguishing feature of this design is the configuration of the portions marked A A, as seen from their side, the same being of a straight-outline configuration on their one surface, b, and of a straight-outline configuration parallel with the surface b on their opposite surface, d, for a part, e, of the length thereof, commencing with the outer ends, c, of said portions A A, and of a tapering-outline configuration inclining inwardly toward the surface b for the greater part of the remainder of the length, as at f. Furthermore, the portions

A A are of a special configuration in transverse section through their surfaces b and d 30 within or throughout the length of the straight and tapering outlines e and f, the same showing a web and flange or T-shaped figure, as shown at e. The inner or lower end portions of the link and the intermediate part between 35 the portions A A may be of any suitable configuration.

I claim—

1. The herein-described design for links of drying-chains of envelope-machines, consisting 40 of a link having a straight-outline configuration on one surface, b, of the portions A A and a partly straight and tapering-outline configuration, e f, on the opposite surface, d, as shown.

2. The herein-described design for links of 45 drying-chains of envelope-machines, consisting of a link having its portions A A T-shaped, one surface, b, of which is of a straight-outline configuration, and its opposite surface, d, of a partly straight and tapering outline configu- 50 ration, e f, as shown.

WALTER E. PREBLE.
